(57) **CLAIM**

The ornamental design for a lighting fixture, as shown and described.

DESCRIPTION

FIG. 1 is a top perspective view of a lighting fixture that has the design.

FIG. 2 is a bottom perspective view of the lighting fixture.

FIG. 3 is a side elevational view of the lighting fixture, the opposite side view being identical.

FIG. 4 is a top plan view of the lighting fixture.

FIG. 5 is a bottom plan view of the lighting fixture.

FIG. 6 is an end elevational view of the lighting fixture, the opposite end view being identical.

FIG. 7 is a top perspective view of a second embodiment of lighting fixture that has the design.

FIG. 8 is a bottom perspective view of that lighting fixture.

FIG. 9 is a side elevational view of that lighting fixture, the opposite side view being identical.

FIG. 10 is a top plan view of that lighting fixture.

FIG. 11 is a bottom plan view of that lighting fixture.

FIG. 12 is an end elevational view of that lighting fixture, the opposite end view being identical.

FIG. 13 is a top perspective view of a third embodiment of lighting fixture that has the design.

FIG. 14 is a bottom perspective view of that lighting fixture.

FIG. 15 is a side elevational view of that lighting fixture, the opposite side view being identical.

FIG. 16 is a top plan view of that lighting fixture.

FIG. 17 is a bottom plan view of that lighting fixture.

FIG. 18 is an end elevational view of that lighting fixture, the opposite end view being identical.

FIG. 19 is a top perspective view of a fourth embodiment of lighting fixture that has the design.

FIG. 20 is a bottom perspective view of that lighting fixture.

FIG. 21 is a side elevational view of that lighting fixture, the opposite side view being identical.

FIG. 22 is a top plan view of that lighting fixture.

FIG. 23 is a bottom plan view of that lighting fixture; and,

FIG. 24 is an end elevational view of that lighting fixture, the opposite end view being identical.

The bottom face of the lighting fixture is generally flat. A thin rim extends around the outer edge and around the illuminated central portion.
